UNITED STATES PATENT OFFICE.

ANTON ZEINDLHOFER, OF VIENNA, AUSTRIA, ASSIGNOR TO GROOVE LOCK CO. INC.,
OF NEW YORK, N. Y., A CORPORATION OF NEW YORK.

RECEPTACLE.

Application filed January 26, 1928. Serial No. 249,566.

This invention relates to improvements in receptacles, particularly receptacles or casings that can be readily opened and closed and provided with means for keeping the receptacle shut.

One object of the invention is to provide a receptacle or casing that is preferably portable and has a lid or closure attached thereto with novel means for engaging the closure to keep the receptacle shut or release the closure to enable the receptacle to be opened.

A further object of the invention is to provide a receptacle that is of strong construction, ornamental in appearance and capable of being easily and inexpensively manufactured.

The objects and advantages of the invention are fully set forth in the description and drawings, which illustrate the best embodiment of my invention now known to me. But I of course reserve the right to make changes not necessarily shown herein but coming within the spirit and scope of the invention and embraced by the broad meanings of the terms in which the appended claims are expressed.

On the drawings,

Figure 1 shows a top view in perspective of a receptacle according to my improvement;

Figure 2 is a front view thereof showing the receptacle closed;

Figure 3 is a similar view, partly in section, showing the receptacle open.

Figure 4 is an enlarged transverse sectional view taken on the line 4—4 of Figure 2.

The same numerals identify the same parts throughout.

In the detailed description of the structure presented in the drawings, the numeral 1 indicates the body of the receptacle and 2 the lid or closure therefor, these two parts being attached to each other by means of a hinge 3. The body 1 comprises a cup-shaped member 4, which receives another cup-shaped member 5; the rim of the member 5 projecting above the rim of the member 4. The parts 4 and 5 may be secured together in any suitable manner, and the hinge 3 is mounted upon the rim of the part 5, which projects outward and forms a circumferential rib 6. The lid 2 is reduced in diameter below the top thereof, thus giving the lid the appearance of having a flange 7; and carried by the reduced portion is an annular rib 8 extending around the

lid 2 but spaced from the flange 7, as indicated more particularly in Figures 2 and 4. Affixed to the rib 8 but slidably mounted thereon, is a fastener element or catch 9 which engages and releases the rim 6 of the member 5, so that the lid 2 can be held in closed position or moved to open the receptacle. This annular part 8 is attached to a ring 10, the portion or web connecting the ring or rib 8 and the ring 10 being indicated at 11, and the ring 10 fits inside of the reduced or contracted portion of the lid above mentioned. This reduced portion is shown at 12, and by expanding the inner edge of the ring 10 within the contracted portion or rim 12 of the lid 2, the ring or rib 8 is securely held on the lid 2. By cutting this ring 8 at suitable points and perforating the portions between the cuts, said portions may be made to serve as parts of the hinge 3, cooperating with similar parts on the rim 6 of the cup 5 to receive the hinge pin and thus connect the body and lid together; and the hinge 3 may of course be a spring hinge to move the lid up when the catch 9 releases the rib 6.

The rib 8 has edges 13 and 14 projecting above and below the web 11, the lower edge 14 also extending down a little beyond the lower edge of the rib 6 on the cup 5, when the lid is closed.

The catch 9 may be C-shaped when viewed from one end or in cross-section; that is to say, it will have its edges bent over the edges 13 and 14 of the rib 8, and the space between the rib 8 and flange 7 indicated at 15 and the similar space or groove 16 between the rib 8 and the rim of the cup 4 will be large enough to allow the catch 9 to have a free movement. Two stops 17, shown in Figure 3, will be provided to limit the movement of the catch 9, and adjacent one of the stops, such as stop 17 at the right in Figure 3, the rib 6 will be provided with a cut-away portion or recess 18. Whenever the catch 9 is moved as far as the stop 17 at the right permits, it will register with the recess 18, which will be as large as the catch, and then the lid can be opened. To close the receptacle, the lid is put down, with the catch 9 in contact with the said stop 17, so that the lower part of the catch will pass through the recess 18, and then the catch is moved to the left, referring to Figures 1, 2 and 3, so as to make it engage once more with the underside of the rib 6. Then the lid

will be secured in closed position to the body 1.

Inside of the lid 2 is a mirror 19, having a ring 20, channel shaped in cross-section, 5 surrounding it. This ring and mirror are encircled by the ring 10 and snugly engaged by it so as to be secured in position.

From the foregoing description it will be clear that the receptacle is very simple in 10 structure, and can be kept securely shut but easily opened.

The rib or rail 8 on which the catch 9 rides, overhangs and screens the rib 6 when the lid is closed, and thus any seam which might 15 appear between the body and closure is completely concealed.

The range movement of the catch 9 from one stop 17 to the other is sufficiently large to enable the catch 9 to be moved a considerable distance away from the recess 18 and thus the risk of the casing ever being opened accidentally is eliminated.

Preferably the outside of the ring 8 is rounded to give a more artistic effect.

25 While the invention is shown as embodied in the form of the receptacle above described, I may obviously practise the invention in connection with receptacles or casings of different shape or construction and still be within 30 the principle of the invention.

Claims:

1. A receptacle, comprising a body, a closure therefor, the body having a rim and the closure having a rib which covers said rim, 35 and a sliding catch mounted on said rib to engage and release the rim.

2. A receptacle, comprising a body consisting of a number of cup-shaped members, one within the other and projecting 40 above the rim of the other, a closure attached to the inner member, a rib carried by the closure to receive the rim of said inner member, and a sliding catch mounted on said rib.

3. A receptacle, comprising a body, a closure attached to the body, said closure having a reduced portion, a rib carried by the closure, a retaining ring within the closure, and a web connecting said ring and said rib.

4. A receptacle, comprising a closure having a body with an outturned rim, a lid pivoted to said body, the lid having a contracted rim, an annular rib attached to the rim of the closure and shaped to receive the rim of the body within it when the closure is shut, 55 and a catch mounted to move on said rib to engage the rim of the body and release same to permit the receptacle to be shut and opened.

5. A receptacle, comprising a body having 60 an outturned rim, a closure attached to the rim of the body and having its rim contracted, a rib surrounding the contracted rim

of the closure and secured to the closure, said rib encircling the rim of the body when the closure is shut, and a catch mounted on the rib movable to engage the rim of the body to keep the receptacle shut, the rim of the body having a recess so that the catch can be moved into registry therewith to enable the receptacle to be opened.

6. A receptacle, comprising a body consisting of members one received within the other, the inner member projecting beyond the rim of the other member and having its rim turned outward, a closure hinged to the 75 rim of the inner member, the closure having a contracted portion, a rib secured to the closure and surrounding the contracted portion and receiving the rim of said inner member within it when the closure is shut, a retaining 80 ring secured to said rib within the closure to hold the rib in position, a mirror having a peripheral ring disposed within the closure and encircled by said retaining ring, and a catch mounted upon the rib to engage the rim of 85 the inner member and hold the receptacle shut, said rim having a recess for the catch to register with and enable the receptacle to be opened, and stops on the receptacle to limit the movement of the catch. 90

7. A receptacle having a body and a movable closure therefor, the latter being provided with a rim, a mirror having a ring encircling it disposed within the closure, and a ring extending within the closure between 95 the ring on the mirror and said rim, so that the mirror is held in place in the closure, said last-named ring bearing a rib which encircles the adjacent portion of the body when the closure is shut.

8. A receptacle having a body and a movable closure, the closure provided with a rim, a mirror having a peripheral ring within the closure and surrounded by the rim, a ring between the ring on the mirror and said rim, 105 a rib encircling the rim and extending beyond the periphery thereof and connected to the second named ring, and means on the rib for holding and releasing said body to enable the receptacle to be kept shut or opened. 110

9. A receptacle having a body and a movable closure, the closure provided with a rim, a mirror having a peripheral ring within the closure and surrounded by the rim, a ring between the ring on the mirror and said rim, 115 a rib encircling the rim and extending beyond the periphery thereof and connected to the second named ring, and means slidably mounted on the rib for holding and releasing said body to enable the receptacle to be kept shut or opened.

In testimony that I claim the foregoing as my invention, I have signed my name hereto.

ANTON ZEINDLHOFER.
